UNITED STATES PATENT OFFICE.

THOMAS S. WILES, OF ALBANY, NEW YORK.

MAGAZINE PHOTOGRAPHIC-PLATE HOLDER.

SPECIFICATION forming part of Letters Patent No. 424,396, dated March 25, 1890.

Application filed December 21, 1888. Serial No. 294,270. (No model.)

To all whom it may concern:

- Be it known that I, THOMAS S. WILES, a citizen of the United States, residing at Albany, in the county of Albany, State of New York, have invented certain new and useful Improvements in Magazine Photographic-Plate Holders, of which the following is a specification, reference being had therein to the accompanying drawings.
- 10 This invention has relation to magazine plate-holders for photographic cameras; and among the objects of the invention are to provide a magazine comprising two compartments—one for the storage and automatic presentation of successive plates of a series for exposure and the other to receive and store plates after exposure, means being also provided for the transfer of plates from the former to the latter compartment.
- 15 Other objects and advantages of the invention will appear in the following description, and the novel features will be particularly pointed out in the claims.

Referring to the drawings, Figure 1 is a central longitudinal section of a magazine constructed in accordance with my invention, the section being taken on the line *x* of Fig. 2. Fig. 2 is a back view of the magazine. Fig. 3 is a plan. Fig. 4 is a transverse section of 30 one-half of the magazine, (no plates being shown therein,) the section being on the line *y* of Fig. 1; and Fig. 5 is a front half of the magazine.

Like letters of reference indicate like parts in all the figures of the drawings.

For clearness in description that side of the magazine which is placed against the rear end of the camera is denominated the "front" and the opposite side the "back."

- 40 The body of the magazine consists of a frame A, the front B of which has an opening B' approximately agreeing in area with the focusing-screen of the camera in connection with which the magazine is to be used. The front adjacent to the opening B' is rabbeted, as at B², to fit into the camera like any ordinary plate-holder. A slide C is provided to close the opening B' and serve as a plate-transferring device, as hereinafter described.
- 45 A septum D separates the main body or frame of the magazine into two compartments E and F. This septum comprises two

plates D', of thin wood or other suitable material, between which a felt, cloth, or other shutter or light-excluding device D² is arranged. In this instance the material is folded upon itself, with its folded edge projecting into the path of the slide C. Above and below the plates D' are placed metal plates D³. Between the plates D' there is inserted a T-shaped bar D⁴, of metal, which extends from side to side and is secured in position by screws or rivets D⁵, which serve also to bind the plates D' D³ and shutter D² in position. The wooden plates D' extend less than the whole distance between the front and back of the magazine, so as to form a chamber D⁶, in which the folded end of the light check or shutter D² may operate, so as to close the opening for the slide whenever the latter is withdrawn. The bar D⁴ is in this instance secured to the frame by screws D⁶. (See Fig. 2.) Any suitable light check may be arranged in chambers or offsets B³, formed at the top of the magazine, through which offsets the slide C passes, so as to prevent access of light at that point.

The frame A is rabbeted at its back edge all around, as shown at A', and this feature of construction, in connection with the T-shaped bar D⁴, adapts the back to receive doors G and G' for the upper and lower compartments E and F, respectively, said doors being rabbeted or otherwise adapted to fit the rabbet of the frame. It is evident that the doors G G' may be hinged to the magazine. Each door is recessed, as at G², and a latch G³ is pivoted within said recess, and is capable of being swung under a plate H, secured to the frame A and projecting over a similar recess H', formed in the frame. By this construction the latch may be turned out of contact with the plate H, as indicated by dotted lines in Fig. 2, and the door swung away from the frame at one edge and withdrawn from under the metal bar D⁴ at the opposite edge, thereby giving access to the compartment closed by the door.

I represents followers, one of which is arranged in each chamber, and each consists, essentially, of a plate I', of suitable material, recessed, as shown, for the reception of the terminal coil of a spring J, which is attached to or may simply bear against the inner sur-

face of the door. The follower I' of the upper compartment is slightly beveled at its top, as at I³, to permit the entrance of the slide when all the plates have been transferred to the lower compartment.

K represents a series of photographic plates in the exposing-compartment, and K' a series of plates arranged after exposure in the receiving-compartment of the magazine. The outer edge of the slide C is provided with a metal binding C', secured by rivets C², and upon this binding is secured a thumb-piece or handle C³, which serves to facilitate the operation of withdrawing the slide. The lower edge of the slide is formed with a projection C⁴ (see Fig. 4) at opposite corners thereof, and the inner surfaces of the side walls of the frame A are grooved, as at A², to a sufficient depth to receive the slide and its projections. A metal plate L (see Figs. 1 and 4) is arranged to project partially over the upper end of the groove A², so as to prevent the complete withdrawal of the slide.

The inner surface of the front B in the upper compartment is coincident with the plane of exposure, while the inner surface of the front of the receiving-compartment is somewhat in front of said plane and has at its lateral edges guides B¹, (appearing in side elevation in Fig. 1,) the surfaces of which are in part coincident and in part inclined to said plane of exposure, as at B^{4xx}. The inclination begins at a point below the septum to provide a guiding-surface in the path of the slide, and terminates at the inner surface of the front and at its lower edge. The inclined portions of the guides cause the follower I and all the plates in said receiving-compartment to assume an inclined position, with their upper ends toward the back, thereby leaving an unoccupied space at the upper front of said compartment and immediately under the lower edge and in the path of the slide C. The object of this construction is to insure the entrance of the front plate of the series in the upper compartment in front of the follower, or any plate or plates in the lower compartment when it is desired to transfer a plate from one compartment to the other. Various constructions to attain this object will suggest themselves to persons skilled in the art. For example, the guides, instead of being limited to the lateral edges of the front wall, may be extended entirely across the same.

B^{4xx} indicates by dotted lines a spring arranged as an equivalent construction. It is secured to the front B below the septum, and its free end projects into the path of the slide C, so as to remove the upper end of the follower and any plate or plates from said path, and thus form the unoccupied space M. In this case the inner surface of the front wall of the lower compartment may be in line with the front wall of the upper compartment. With this construction the inclination in part or in whole of the wall is unnecessary. In the one case the inclined guides are fixed

and in the other they are yielding; and in both cases points of resistance to the pressure of the follower are provided, which so disposes the same or plates thereagainst as to produce the desired unoccupied space.

N is a corner-plate secured at the top of the frame, and by means of screws N' may assist in binding the back and body of the magazine together, and it also presents a metallic surface, against which the head of the slide abuts when it is closed.

In order to insure a smooth movement of the slide C, I have provided devices which control it when being entered or withdrawn in such a manner that one edge shall not advance faster than the other, and therefore cannot bind in the grooves A² of its receiving-frame A. Ordinarily, in plate-holders provided with slide-controlling devices, if the force used to enter or withdraw a slide is not applied in a right line in the direction of the desired movement of the slide, the latter is diverted laterally from its normal path and caused to bind at its opposite edges, and in correcting this divergence in one direction liability exists in causing a like divergence in an opposite direction, and the result is a hitching or jerky movement of the slide, which displaces the camera from a previous adjustment and necessitates a repetition of focusing. By my invention this difficulty is overcome.

Referring to Figs. 1 and 2, O' O² O³ O⁴ represent links pivoted at one end to a connecting-bar O⁵. At the opposite end the links O' and O³ are pivoted to the slide—as, for example, as at O⁶ O⁶—while the ends of the links O² O⁴ are pivoted to a fixed part—for example, on the frame O⁷. The inner ends of the links may be square, as shown at O⁸, so as to abut against each other and act as a stop against further movement when the links of each pair are brought in line with each other. The plate O⁵ may be extended beyond its link-pivots, as clearly shown, and its ends may then serve as means for opening or closing the links. The links may be pivoted to either or both surfaces of the connecting-bar. By this example of a slide-controlling device it will be seen that when force is applied to enter or withdraw the slide said force is caused to act in a direct line with the normal path of the slide and a smooth movement of the latter is assured.

This being the construction, the operation is as follows: After the operation of focusing, the magazine, having a series of plates in its upper compartment, is applied to a camera. The slide is now withdrawn and the series of plates is advanced by the spring-follower a distance equal to the thickness of the slide, thus bringing the front plate of the series into the same vertical plane as the slide and against the exposure-opening B'. The plate is exposed, and the cap or shutter of the camera is then closed and the slide forced in, carrying before it the exposed plate, which is

caused to pass the shutter D^2 , into the space M in front of the follower, or in front of any plate or plates in the lower compartment, until said exposed plate is wholly within the 5 lower compartment, the follower by means of the spring J yielding to make room for the exposed plate. As soon as the exposed plate and the lower edge of the slide passes below the upper surface of the septum D , a fresh 10 plate is, by the spring J and follower I of the upper compartment, brought against the slide, and when the latter is withdrawn for exposure said spring and follower forces the plate into the position occupied by the slide. The 15 thickness of the front is such as to bring a plate in the upper compartment in the same plane as that occupied by the focusing-screen. The follower I , being slightly beveled at the top, permits the entrance of the slide after all 20 the plates have been exposed and transferred to the lower compartment.

For the purpose of close packing for transportation or storage, the magazine is provided with a hinge Q , (see dotted lines, Fig. 1,) the 25 magazine being separated on the line Q' , and any suitable fastening being also used to lock the parts in operative position.

I am aware that a plate-holder adapted to hold and expose only a single plate has been 30 hinged to a storing-chamber; but in such case a light-proof bag was used to transfer plates from the holder to the storing-chamber. In my invention the receiving-chamber communicates in a light-proof manner with the part 35 serving the function of a plate-holder.

Having described my invention and its operation, what I claim is—

1. A magazine plate-holder of the class described, having the lateral margins of the inner front wall of its receiving-compartment 40 inclined, substantially as specified.

2. A magazine plate-holder of the class described, having two compartments, the inner surface of the front walls of one compartment 45 lying in the plane of exposure and the other compartment having inclined guides on the lateral margins of the inner surface of its front wall, substantially as specified.

3. A magazine plate-holder of the class described, having two compartments, the inner surface of the front walls of one compartment lying in the plane of exposure and the other compartment having fixed inclined guides on the lateral margins of the inner surface 55 of the front wall, substantially as specified.

4. A magazine plate-holder of the class described, comprising two compartments, one of which is provided with an exposure-opening and with a slide for closing said opening, and the other compartment of which is provided with a front wall, the lateral margins of the inner surface of which are provided with guides inclined with relation to the inner surface of the front of the first-mentioned compartment, substantially as specified. 60

5. A magazine plate-holder of the class described, comprising a septum dividing the magazine into two compartments and having a shutter arranged thereat, and a slide for closing the exposure-opening of the upper compartment and projecting across the septum, the compartment beyond the septum having inclined guides, substantially as specified. 70

6. In a magazine plate-holder of the class described, a septum comprising separate plates and a shutter made of fabric inserted between the plates, substantially as specified. 75

7. A magazine plate-holder of the class described, comprising a septum of separate plates and a T-bar secured thereinbetween, and forming a groove for the reception of a door, substantially as specified. 80

8. A magazine plate-holder of the class described, comprising a septum formed of plates and interposed fabric constituting a shutter, metal plates projecting to form a chamber for the shutter, and a T-bar, substantially as specified. 85

9. The combination, with the slide and its receiving-frame, of links and a connecting-bar, substantially as specified. 90

10. The combination, with a slide and its receiving-frame, of links having square inner ends and a connecting-bar, substantially as specified. 95

11. The combination, with a slide and its receiving-frame, of links having square ends and a connecting-bar extending beyond its link-pivots, substantially as specified. 100

12. A magazine plate-holder having its exposing-chamber and its light-proof communicating receiving-chamber joined by a hinge, substantially as specified. 105

In testimony whereof I affix my signature in presence of two witnesses.

THOMAS S. WILES.
